GAME BOARD

John Di Amico, 5627 McMahon St.,
Philadelphia, Pa. 19141

Filed Sept. 26, 1966, Ser. No. 4,033

Term of patent 14 years

(Cl. D34—5)

The figure is a plan view of a football game board of conventional thickness.

The essential features of the design are shown in full lines.

I claim:

The ornamental design for a game board, as shown and described.
